(57) **CLAIM**

The ornamental design for automobile tire, as shown and described.

DESCRIPTION

FIG. 1 is a front view of an automobile tire, showing the new design, the rear view, the top plan view and the bottom plan view appearing the same as the front view;

FIG. 2 is a right side view of the tire, the left side view appearing the same as the right side view;

FIG. 3 is a fragmentary front view, showing in enlargement the portion of lines 3—3 in FIG. 1; and,

FIG. 4 is a cross-sectional view taken along line 4—4 and in the direction of arrows in FIG. 3.
